UNITED STATES PATENT OFFICE.

BEN K. FORD, OF DETROIT, MICHIGAN, ASSIGNOR, BY MESNE ASSIGNMENTS, TO DETROIT CAN COMPANY, OF DETROIT, MICHIGAN, A CORPORATION OF NEW JERSEY.

CAP-GUMMING MACHINE.

1,071,637.

Specification of Letters Patent. Patented Aug. 26, 1913.

Application filed February 2, 1910. Serial No. 541,622.

To all whom it may concern:

Be it known that I, BEN K. FORD, a citizen of the United States of America, residing at Detroit, in the county of Wayne 5 and State of Michigan, have invented certain new and useful Improvements in Cap-Gumming Machines, of which the following is a specification, reference being had thereto in to the accompanying drawings.

- 10 It is the object of the invention to provide means for quickly applying adhesive material to packages, and particularly to paper packages, so as to seal the same upon closure.
- 15 To this end, the invention consists in the means for gumming the flange of the cap for the package on the inner face thereof, so that when placed on the package the sealing will be effected.
- 20 In the drawings—Figure 1 is a vertical central section through the machine; and Fig. 2 is a horizontal section on line X—X, Fig. 1.

A is the head adapted to fit within the 25 cap of the package. This head is chambered at B and is provided with small ports or openings D at the periphery communicating with said chamber. These ports are so arranged that when the paper cap is 30 placed on the head the flange thereof, indicated in dotted lines, will cover the ports.

The chamber B is filled with a suitable 35 adhesive material, which normally stands at a level, slightly below the port openings D. There is also provided means by which when the cap is placed on the head, the level of the adhesive material is raised, thereby permitting it to pass through the ports and coat the inner face of the cap. Furthermore, before removal of the cap, the level 40 is again lowered, thereby preventing escape of the material when the cap is removed.

The means for performing the functions just described, which I preferably employ, is 45 of the following construction: The head A is provided with a vertically and downwardly-extending shank F, which slidably engages a bearing in a member G. At the lower end of the shank F is attached a flexible dia- 50 phragm H, which covers a well I formed in a base member J, the member G forming a cap above said base member. K are stops for limiting the downward movement of the head, and L is a spring on the shank F, which yieldably supports the head in a 55

predetermined position. M is a conduit for supplying the adhesive material to the chamber I, and N is a receptacle for holding the supply of material preferably in the form of an inverted container, having its lower 60 end sealed by the liquid in a cup O. The arrangement is such that a constant level of the fluid adhesive material is maintained in the cup O and in the chamber B which communicates through the hollow shank F with 65 the chamber I, and this level is slightly below the ports D when the head A is in normal position.

In operation, the cap to be gummed is placed upon the head A and a slight downward pressure is applied, which will depress the said head against the tension of the spring L. This will cause a pressure upon the diaphragm H, which will depress the same, displacing the material in the chamber 75 I, and forcing it upward through the hollow shank F until the level in the chamber B is above the ports D, and the adhesive is applied to the inner face of the cap flange. Upon releasing the pressure the spring L 80 will raise the head, lifting the diaphragm H and again lowering the level within the chamber B to below the ports. During this operation, the escape of the liquid through the supply port M is prevented by a check 85 valve, such as P.

To adapt the machine for use with various sizes of caps, different sizes of heads A are constructed to interchangeably engage the shank F and any desired size may be selected 90 according to the requirements of the particular work.

What I claim as my invention is:

1. A cap gumming machine, comprising a chambered head having a peripheral face 95 conforming in shape and size to and adapted to engage the interior of the cap flange, said face having ports covered by the cap flange, a chambered member, a diaphragm covering the chamber in said member, a hollow shank 100 connecting said diaphragm with said head and forming a communicating passage between the chamber in said member and the chamber in said head, and means for yieldably supporting said head permitting of the 105 depression thereof for the purpose described.

2. A cap gumming machine, comprising a chambered head having a peripheral face conforming in shape and size to and adapted to engage the interior of the cap flange, said 110

free having ports covered by the cap flange, a chambered member, a hollow displacement member therein connected with said chambered head, means for yieldably supporting said head whereby the depression thereof will displace the fluid adhesive material in said chambered member and raise the level within the chamber in said head, and means arranged exteriorly of said chambered member and said head for limiting the depression of the latter.

3. A cap gumming machine, comprising a chambered head having a peripheral face conforming in shape and size to and adapted to engage the interior of the cap flange, said face having ports covered by the cap flange, a chambered member, a hollow displacement member therein connected with said chambered head, means for yieldably supporting said head whereby the depression thereof will displace the fluid adhesive material in said chambered member and raise the level within the chamber in said head, and means

upon the exterior of the chamber positioned in the path of the head for limiting the depression of the latter.

4. A cap gumming machine comprising a chambered head having a peripheral face conforming in size and shape to and adapted to engage the interior of the cap flange, said face having ports covered by the cap flange, a chambered member, a hollow displacement member therein connected with said chambered head, and means exterior of the chambered member for yieldably supporting said head whereby the depression thereof will displace fluid adhesive material in said chambered member and raise the level within the chamber in the head to the peripheral ports.

In testimony whereof I affix my signature in presence of two witnesses:

BEN K. FORD.
